F. D. SCHOLL,
AUTOMATIC DIVIDER BLOCK FOR HAY PRESSES,
APPLICATION FILED NOV. 10, 1915.

1,232,984.

Patented July 10, 1917.

UNITED STATES PATENT OFFICE.

FRANK D. SCHOLL, OF GRANVILLE, NORTH DAKOTA.

AUTOMATIC DIVIDER-BLOCK FOR HAY-PRESSES.

1,232,984.

Specification of Letters Patent. Patented July 10, 1917.

Application filed November 10, 1915. Serial No. 60,777.

To all whom it may concern:

Be it known that I, FRANK D. SCHOLL, a citizen of the United States, residing at Granville, in the county of McHenry, State 5 of North Dakota, have invented a new and useful Automatic Divider-Block for Hay-Presses; and I do hereby declare the following to be a full, clear, and exact description of the invention, such as will enable others 10 skilled in the art to which it appertains to make and use the same.

This invention relates to the art of presses, particularly hay presses, and more especially to an automatic gravitating spring starting 15 divider block, for dividing the hay as it is fed into the baling chamber of the press, into bales.

One of the objects of the invention is to provide a device of this kind, in which improved, novel and practical features of construction are involved.

Heretofore, in the operation of baling presses, a pause or stop occurs in the baling, at every two or four strokes of the plunger, 25 thereby consuming excessive time. Hence, the object of the present invention is to provide an automatic gravitating divider block, spring started, to eliminate the pause or stop, or intermissions between the bales, and 30 to provide a machine, in which the baling is continuous and uninterrupted.

In practical fields, the details of construction may necessitate alterations falling within the scope of what is claimed.

35 The invention comprises further features and combination of parts, as hereinafter set forth, shown in the drawings, and claimed.

In the drawings:—

Figure 1 is a plan view of a portion of a 40 baling press, showing the improved automatic gravitating spring started divider block applied thereto.

Fig. 2 is a view in side elevation.

Fig. 3 is a view in elevation, showing the 45 opposite side.

Fig. 4 is a detail sectional view through the divider block and its guide and supporting means.

Fig. 5 is a perspective view, showing the 50 upper end of the element 28, a part of the rod 31 and the block 35.

Referring more especially to the drawings, 1 designates a casing of the baling press, in the baling chamber of which the usual or conventional plunger 2 is mounted, which 55 plunger is provided with the usual or conventional plunger rod 3, which may be operated in any suitable manner, not shown. Projecting from one side of the plunger 2 and extending through a slot 4 in one side of the casing 1 is a laterally extending pin or lug 5. Rising upwardly from the casing 1 near one end is an arch guide 6, in which the automatically actuated gravitating spring started divider block 7 is mounted. Mounted in suitable bearings 8 is a rock shaft 9, the ends of which terminate in forwardly and downwardly extending arms 10 and 11. The arms 10 and 11 are provided with laterally extending lugs 12. Extending transversely of the arch guides 6 and arranged normally adjacent the upper wall thereof is a plate 13, both ends of which extend partially downwardly and outwardly and terminate in the extension plates 14, upwardly 60 through which the upper portions of the rods 15 extend, so that said extension plates will rest upon the collars 16, which are integral with said rods 15. The lower ends of the rods 15 are pivotally connected by the 65 pins 17 to the lugs 12. Upon the upper ends of the rods 15 are washers 18, between which and said extension plates 14, springs 19 are interposed, there being nuts 20 threaded upon the upper ends of the rods 15, so that 70 by adjusting the nuts, the tension of springs 19 may be increased or decreased. The rock shaft 9 substantially centrally thereof has fixed to it a downwardly extending arm 21, to the lateral extensions 22 of which a supporting tongue 23 is fixed, so that when the rock shaft 9 is in the position shown clearly 75 in Figs. 2 and 4, this supporting tongue engages under the divider block, to support the same, as clearly shown in Fig. 4. The arm 10 of the rock shaft has an eye 24, to which one end of the spring 25 is connected. The other end of the spring 25 is connected to a lug 26 rising upwardly from the casing 80 1 of the baling press. Pivoted by means of 100 a bolt 27 to one side of the baling press casing is a lever 28, the lower end of which

has a laterally extending lug 29 which extends partially through the opening 30 in one side of the casing of the baling press. A rod 31 is connected pivotally by a pin 32 to the lower extremity of the arm 10, as shown in Fig. 3. The lever 28 at its upper end, as shown in Fig. 1, is provided with an eye 28 through which one end portion of the rod 31 extends. Slidably adjustable on the rod 31 is an abutment 35, the opposite walls of which have apertures 36, to receive a pin 37, which may pass through any one of the apertures 38 of the rod 31, to hold the abutment in adjusted positions.

15 As the divider blocks are needed, they are placed into the arch guide from one side thereof, to be supported by the tongue 23, as shown clearly in Fig. 4. As a bale passes out through the baling press chamber, the 20 lever 28 is tripped or tilted on its pivot, by the bale or the wire thereon coming in contact with the inwardly projecting part 29. When the lever 28 is rocked or tripped, the eye 28 will contact with the abutment 35, thereby pushing the rod 31 sufficiently in order to rock the rod 9 against the action of the spring 25, so as to bring the lower extremity of the arm 11 in the path of the pin or lug 5, at the same time the lug or 25 pin 5 reaches the lower extremity of the arm 11. This occurs when the plunger 2 is on its backward movement, and after the lug or pin 5 engages the lower extremity of the arm 11, and the plunger 2 proceeds farther 30 on its backward movement, the rod 9 is not only rocked sufficiently to withdraw the supporting tongue 23 from under the divider block, but also forcibly and quickly start the divider block on its downward movement 35 between the bale of hay and the plunger, that is, when the plunger reaches its farthest movement rearwardly. The divider block is started forcibly downwardly and yieldably by means of the springs 19, owing 40 to a pull upon the rods 15, which are connected to the arms 10 and 11 of the rock rod 9. For instance, when the rock rod or shaft 9 is rocked, a pulling action is imparted to the rods 15, in which case the 45 washers 18 will press upon the springs 19, and the plate 13 will bear on the divider block 7 yieldably, especially before the plunger has moved from under the block, which has been previously released from the tongue 50 23 so as to rest upon the plunger. Just so soon as the plunger on its rearward movement pulls or removes from under the block, which the springs 19 are tensioned to such a degree, that they forcibly cause the divider 55 block to quickly gravitate between the bale of hay and the plunger, after which the plunger moves forwardly again and drives the bale through the baling chamber. As 60 the plunger moves forwardly, the rod or

shaft 9 rocks in the reverse direction by the action of the spring 25, and restores the plate 13 to its initial position in the upper part of the arch guide 6, so that another divider block may be inserted.

The invention having been set forth, what is claimed as new and useful, is:—

1. In combination with a baling press casing having a baling chamber and a plunger operable therein, a guide on said casing, a divider block mounted therein, a rocking element having downwardly and forwardly extending arms, and provided with a member to support the divider block in said guide, spring means connected to one of the arms of said element whereby said member is held under the block to support the same, a device in the upper part of the guide and resting upon the divider block, means connected to said arms of the element and having yieldable connections with said device to force the divider block between the bale and the plunger, when said member is withdrawn from under the block, and means for rocking the element.

2. In combination with a baling press casing having a baling chamber and a plunger operable therein, a guide on said casing, a divider block mounted therein, a rocking element having downwardly and forwardly extending arms, and provided with a member to support the divider block in said guide, spring means connected to one of the arms of said element whereby said member is held under the block to support the same, a device in the upper part of said guide and resting upon the divider block, means connected to said arms of the element and having yieldable connections with said device to force the divider block between the bale and the plunger, when said member is withdrawn from under the block, and means for rocking the element, said means consisting of a rod connected to the lower end of one of the arms, a pivoted trip lever to be tripped by a tied bale of hay, an abutment on said rod, and means carried by the trip lever to engage said abutment to impart a partial rocking movement to the rocking element, to move its other arm in the path of a member on the plunger, and a member on the plunger to engage said other arm and rock the element as the plunger is completing its rearward movement, so as to tension the yieldable connections with said device, to force the block between the bale and the plunger as soon as the plunger completes its rearward movement.

3. In combination, a baling press casing, a plunger in the baling chamber thereof, a guide on said casing, a gravitating divider in said guide, a device having means to support the divider temporarily, means to actuate said device, whereby its means will re-

lease the divider to allow it to engage the top of the plunger, spring means coöperating with the divider and having connections with the device, whereby upon further movements of the device, said spring means is tensioned, so as to force the divider between the bale and the plunger, when the plunger

is removed from under the divider, and means carried by the plunger for further operating said device.
